(57) **CLAIM**

The ornamental design for razor packaging, as shown and described.

DESCRIPTION

FIG. 1 is a perspective view of a showing my new design for razor packaging in which the top portion of the packaging is blue, the product label is white, and the area of the packaging behind the vertical word "Venus" is white;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The dashed broken lines are directed to the environment and are for illustrative purposes only and form no part of the claimed design. The striping indicates the blue color of the top portion of razor packaging.
